CLAIM

The ornamental design for a ceiling lamp as shown and described.

DESCRIPTION

FIG. 1 is a front top perspective view of a ceiling lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash broken lines immediately adjacent to the solid line regions represent the bounds of the claimed design and form no part thereof. The dash-dash broken lines depicting the remainder of the ceiling lamp form no part of the claimed design. The ceiling lamp includes two symbolic breaks. The appearance of any portion of the ceiling lamp between the dot-dash broken lines indicated by brackets forms no part of the claimed design.
